UNITED STATES PATENT OFFICE.

DANIEL W. EGNER, OF LINTHICUM HEIGHTS, MARYLAND.

CABINET.

Application filed August 16, 1922. Serial No. 582,111.

To all whom it may concern:

Be it known that I, DANIEL W. EGNER, a citizen of the United States, residing at Linthicum Heights, in the county of Anne Arundel and State of Maryland, have invented certain new and useful Improvements in Cabinets, of which the following is a specification.

This invention relates to improvements in kitchen cabinets, and has for its object to provide a simple, cheap and efficient arrangement whereby persons using said cabinet may be able to reach any article on the upper shelves thereof.

The invention consists of the novel construction and arrangement of the parts and combination of parts hereinafter more fully set forth in the following specification and pointed out in detail in the appended claims.

In the accompanying drawings,—

Figure 1 is a front elevation of a cabinet having my invention applied thereto.

Figure 2 is a side view of Figure 1, with the upper drawer partly out and showing the folding step in position for use.

Figure 3 is an enlarged detail front elevation of the step and legs.

Figure 4 is an edge view of Figure 3.

Referring to the accompanying drawings, forming part of this specification, and in which like reference numerals designate like parts throughout the several views thereof, 1 designates a cabinet having a number of shelves 2 and two hinged doors 3. In the lower part of the cabinet are two drawers 4 and 5, both of which are adapted to slide in and out of the cabinet and are each provided with a handle 6. The drawer 4 is provided with a hinged step 7 hinged at 8 to the lower edge of said drawer 4. The said step 7 is formed of thin metal, such as steel, or other suitable material and has an opening 9 through which the handle 6 of the drawer 4 projects when the step is folded back against the front of the said drawer 4. The said step 7 is provided with legs 10 integral with the transverse bar 11, which latter is held in position on the step 7 by burning the upper edge 12 over said bar 11. When it is desired to reach an article on any of the upper shelves of the cabinet, the step 7 is lowered with the

legs 10 resting on the floor. A person can then stand upon said step and reach the desired article. The step 7 is also provided with a chain 13 which will hold it in position should the legs move, and will also hold the step in position until the legs can be adjusted. When the step 7 is not in use it is folded up against the front of the drawer 4, as shown in Figure 1, and the said drawer can be moved in and out without interfering with the step 7. The step can be used also when the drawer is partly out, as shown in Figure 2 of the drawing.

Having thus described my invention, what I claim is:

1. A cabinet having a number of shelves in the upper part thereof, a drawer below said shelves adapted to be moved in and out of said cabinet, and a step hinged to said drawer and adapted to be raised or lowered thereon.

2. A cabinet having a number of shelves in the upper part thereof, a drawer below said shelves adapted to be moved in and out of said cabinet, a step hinged to said drawer and adapted to be raised or lowered thereon, and legs pivoted to said step and adapted to hold the said step in the adjusted lowered position.

3. A cabinet having a number of shelves in the upper part thereof, a number of drawers below said shelves adapted to be moved in and out of said cabinet, a step hinged to one of said drawers and adapted to be moved with said drawer, legs pivotally connected to said step and adapted to hold the latter in the adjusted lowered position.

4. A cabinet having a number of shelves in the upper part thereof, a number of drawers below said shelves and slideable in and out of said cabinet and each having a handle on the front thereof, a step hinged to one of said drawers and having an opening therein through which the handle of the drawer projects, legs pivoted to said step, and chains each having one end secured to the step and its opposite end secured to the upper part of the drawer to which the step is hinged.

In testimony whereof I affix my signature.

DANIEL W. EGNER.
